SPECIMEN BLADE SHARPENER

Julius Lipshaw, Detroit, Mich.

Application January 27, 1941, Serial No. 376,055

8 Claims. (Cl. 51—65)

This invention relates to a sharpening machine and has particularly to do with an apparatus for sharpening blades for histological specimens.

Probably the sharpest knives used are found in histology laboratories. These knives are used for cutting extremely thin slices of animal tissue which has previously been frozen in paraffin. After these slices are obtained they are placed under a microscope and studied for such diseases as cancer and the like. A considerable number of these knives are used in such laboratories and the problem of keeping them to the proper keenness is a problem with which this invention is concerned.

An object of the invention is to provide an automatically operating machine for sharpening these knives, such machine to be operated by power.

A further object of the invention is to provide a sharpening machine in which there is no danger of breaking the edge of a blade being sharpened and in which a control is maintained between the blade and the sharpening surface to insure proper contact at all times.

Another object of the invention is to provide a machine which may be changed from a honing machine to a stropping or finishing machine without altering the adjustments.

A further object is to provide a novel control for the pressure maintained between the knife edge and the sharpening surface.

Other objects and features of the invention, having to do with details of construction and operation, such as the speed of relative movement of the blade and sharpening surface, will be brought out in the following description and claims.

In the drawings:

Fig. 1 is a plan view of the machine.

Fig. 2 is a side elevation.

Fig. 3 is a side elevation of the top portion of the machine showing the control belts in different relative positions.

Fig. 4 is an end view of the upper working elements.

Figs. 5 and 6 are sections taken on the lines 5—5 and 6—6 respectively, of Fig. 4.

Fig. 7 is an end view of a sharpening element illustrating the cam construction.

Figs. 8 to 12 illustrate movement of the knife blade during the honing operation.

Figs. 13 to 17 illustrate movement of the knife blade during a stropping or finishing step.

A frame 20 supports tracks 21 on which is 55

reciprocally mounted a table 22. Rollers 23 serve to facilitate the reciprocation of the table on the tracks. The reciprocation is effected by a mechanism which consists of a depending beam 24 on which is a slide rod 25. A bushing 26 on the slide rod is connected to a crank arm 27 mounted on a pulley 28. The pulley 28 is driven by a series of belts and pulleys from a motor 30. At each end of the table 22 are upstanding brackets 32, each provided with a notch 33 at the top thereof. These notches are adapted to receive respectively, bolts 34 and 35, mounted centrally of the ends of a plate 36 of Fig. 1, or a plate 36a of Fig. 3. On plate 36 is mounted a sharpening stone 37 having a honing surface. Plate 36 is provided with wings 38 centrally located at each side, each wing being provided with a cammed portion 39 and 40 at its respective ends.

Centrally mounted on frame 20 is a U-shaped beam 45 having slides 46 on the vertical arms. A second U-shaped member 47 has its vertical arms mounted in said slides 46. Guide bolts 48 are mounted on member 47 and project up through member 45 to insure proper movement of the member 47 when it is shifted up and down by an adjustment screw 49. A hexagonal member 50 turns with the screw 49 and one surface is always in contact with a rocking arm 51 held by a spring 52.

Mounted transversely of the table 22 and plate 36 and stone 37 is a bar 60. This bar has shafts 61 extending from each end thereof and rotatably mounted in the vertical arms of member 47. The vertical arms of member 45 are slotted at 62 to receive projections 63 of shafts 61 on which are mounted pulleys 64. The bar 60 may, therefore, be rotated in its position by turning the pulleys 64. This bar is adapted to serve as a blade holder, as shown more particularly in the sectional view of Fig. 5. Spring plates 65 are bent in such a manner as to correspond to the angles of a blade 66. It will be seen that when the knife edge is resting on the stone surface, as shown in Fig. 5, the raising or lowering of bar 60 by means of adjustment screw 49, will cause a change of the angle of contact between the edge of the blade and the stone. This adjustment can be carefully regulated by reason of the hexagonal control member 50 and also by means of a protractor 68 mounted on member 47 and a pointer 69 mounted on bar 60, see Fig. 6.

At each end of bar 60, mounted on shafts 70, are rollers 71 positioned relative to plate 36 so

that they will contact the ends of wings 38. At the ends of the respective sides of table 22 are mounted angles 72 and 73. These angles have vertical portions between which are suspended pairs of vertically spaced belts. The top pair will be referred to as belts 74 and the lower pair will be referred to as belts 75. The tension of each of the belts may be controlled by adjusting nuts 76 against springs 77.

In the operation, a blade is first inserted in 10 between the holders 65 of bar 60 and adjustment screw 49 is shifted until the desired angle between the blade edge and the stone is obtained. Belt 74 is then passed underneath the pulleys 64. The motor 30 may now be started and table 22 will start reciprocating on the frame 20. The limits of travel of the table are shown in Fig. 1 by the dotted lines. Since the U-members 45 and 47 are mounted on the frame, they will remain stationary relative to the table. In using a stone 15 for sharpening, the surface is to travel toward the edge of the blade 66, as shown by the arrow in Fig. 1. Therefore, when belts 74 start shifting with the table, the pulleys 64 will be rotated by the belts to swing the arm 66 to the position 20 shown in Figs. 1 and 2. After the blade comes in contact with the stone, as shown in Fig. 1, the pulleys 64 can no longer rotate and the result will be that the belt 74 will slide in the pulleys until the table reaches the end of its stroke. The 25 tension of the belts is to be adjusted to the point where this sliding may exert just a definite amount of pressure between the blade and stone. As the table reaches the end of its stroke, it will shift its direction of movement and this shifting will cause the belts to reverse their movement. Since the blade 66 is free to move upwardly, the 30 pulleys will again rotate to swing the blade and bar 60 around so that the blade will contact the stone on its return movement. Thus, at the end of each stroke the blade will be shifted so that it is always in the proper relation to the stone.

Means are provided for controlling the movement of the blade toward the stone. These are the wings 38 and the cam portions 39 and 40 co-operating with the rollers 71 on arms 76. The wings and rollers are so arranged that as the blade is shifted at the end of the stroke and it approaches the stone, the rollers will contact the wings 38 and gradually roll downwardly on cams 39 or 40 to bring the edge of the blade gently in contact with the stone. This movement is illustrated in Figs. 8 to 12. The blade 66 and the bar 60 and the rollers 71 are stationary relative to the wing 38 which is moving in the direction shown by the arrow. As the wing moves, roller 71 rides down on the surface 39 and the blade is brought into contact with the surface of the stone represented by the dot-dash line.

In Fig. 10, the reversing movement of the blade is shown with the wing 38 reversing its movement and falling under the roller 71 in Fig. 11. Then as the reversing of the table continues, the roller 71 moves down the cam surface 40 to bring the blade again in contact with the stone.

In stropping and finishing the edge of a blade, a different movement is used. The surface then moves away from the edge of a blade. The plate 36a, shown in Figs. 3 and 7, is utilized for stropping and finishing. On one side a strop surface 80 is provided and on the other side a strop surface 81 is provided to strop a blade. The plate 36 is removed from the machine by loosening the bolts 34 and 35 and lifting the plate 36 out of its position. The stropping plate 36a may then be

inserted and fastened by the same bolts 34 and 35. In stropping, the lower belts 75 are used and these are brought around the top of the pulleys 64 so that as the device is viewed in Fig. 3, when the table and the plate are moving in the direction of the arrow, the pulleys 64 and the rollers 71 will be positioned as shown and the stropping surface 80 will be moving away from the edge of the stone. At the end of the stroke of the table when reversal takes place, the belt 75 will shift the pulley and swing the knife around. On the plate 36a are formed cam surfaces 84 and 85. It will be understood, of course, that with the use of the belt reversing system, it is necessary that the table actually start on its reverse movement before pulley 64 will be shifted to raise the blade from its sharpening surface. When leather strops are used for the finishing surface, it is essential that the blade be lifted from the plate prior to the reversal, otherwise the leather will be cut. As the table is shifting in Fig. 3, the roller 71 has just left cam surface 85, see Figs. 13 and 14, and blade 66 has been gently lowered to the surface of the strop. As the movement of the table continues in the direction of the arrow, rollers 71 will be contacted by cam surface 84 and lifted, as shown in Figs. 15 and 16. Reversal of reciprocation then takes place and blade 66 is moved around to start the new movement. In stropping, therefore, there is maintained definite control of the blade as it goes toward and away from the sharpening surface. After the stropping, the blade may be finished by turning over plate 36a and presenting a smooth finishing leather surface. The action of the cams is the same in the finishing step as it was in the stropping step.

It will be seen that due to the central mounting of plates 36 and 36a, the sharpening surface 37 or 80, 81 will be, in effect, floating surfaces, that is, they may pivot about the axis of the bolts 34, 35. This is highly desirable since it permits the blade to establish its own contact with the sharpening surface and prevents undue wear at any one end of the plate. Means must be provided, however, for controlling the floating of the sharpening surface and this is accomplished in the present case by cooperation between the rollers 71 and the wings 38 or cams 84, 85, as the case may be. The rollers always contact the wings or cams prior to the time the blade contacts the surface and since these rollers are mounted at each side of the apparatus, the sharpening surface will receive a predetermined balancing effect each time the blade approaches the surface. After contact has been made between the blade and the surface, the rollers leave the wings or cams and the blade may find its own balance with the sharpening surface. There is, therefore, a controlled floating contact between the blade edge and the sharpening surface.

It will be seen that with the above device there is such control maintained that breakage of blade edges is impossible and the cutting of strops is also definitely avoided. Furthermore, the device is arranged in such a manner that it will proceed in its sharpening automatically and may be left to run for any length of time desired without the attention of an operator.

It is understood, of course, that the improvements shown are intended to be illustrative only, and that the breadth of the invention is evidenced by the following claims.

I claim:

1. In a sharpening device for histological specimen blades, a frame, a table on said frame, means to shift said table on said frame in reciprocal strokes, a sharpening element mounted on said table having a sharpening surface, a blade holder, means supporting said blade holder transversely of said table and for pivotally mounting said holder whereby it may be shifted relative to said table, means for adjusting the level of said blade holder whereby the angle contact of a blade held therein with a sharpening surface may be regulated, pulley means on said blade holder and belt means on said table cooperating to effect a shifting of said blade holder at the end of each stroke of said table, and means on said blade holder and said sharpening element for controlling the rate of movement of a blade in said holder with the sharpening surface of said sharpening element at the end of each stroke, said last named means comprising rollers at each end of said holder and cams on said sharpening element which contact during one portion of movement of said table to control the movement of a blade in said holder toward or away from the sharpening surface of the sharpening element and to control the position of the sharpening element relative to the holder.

2. In a sharpening device for histological specimen blades, a frame, a table on said frame, means to shift said table on said frame in reciprocal strokes, a sharpening element mounted on said table having a sharpening surface, a blade holder, means supporting said blade holder transversely of said table and for pivotally mounting said holder whereby it may be shifted relative to said table, means for adjusting the level of said blade holder whereby the angle contact of a blade held therein with a sharpening surface may be regulated, pulley means on said blade holder and belt means on said table cooperating to effect a shifting of said blade holder at the end of each stroke of said table, and means on said blade holder and said sharpening element for controlling the rate of movement of a blade in said holder with the sharpening surface of said sharpening element at the end of each stroke.

3. In a sharpening device for histological specimen blades, a frame, a table on said frame, means to shift said table on said frame in reciprocal strokes, a sharpening element mounted on said table having a sharpening surface, means for movably supporting said element on said table whereby said element may be pivoted about an axis parallel with the direction of movement of said table, a blade holder, means supporting said blade holder transversely of said table and for pivotally mounting said holder whereby it may be shifted relative to said table, means for adjusting the level of said blade holder whereby the angle contact of a blade held therein with a sharpening surface may be regulated, pulley means on said blade holder and belt means on said table cooperating to effect a shifting of said blade holder at the end of each stroke of said table, and means on said blade holder and said sharpening element for controlling the rate of movement of a blade in said holder with the sharpening surface of said sharpening element at the end of each stroke.

4. In a sharpening device for histological specimen blades, a frame, a table on said frame, means to shift said table on said frame in reciprocal strokes, a sharpening element mounted on

said table having a sharpening surface, means for movably supporting said element on said table whereby said element may be pivoted about an axis parallel with the direction of movement of said table, a blade holder, means supporting said blade holder transversely of said table and for pivotally mounting said holder whereby it may be shifted relative to said table, means for adjusting the level of said blade holder whereby the angle contact of a blade held therein with a sharpening surface may be regulated, pulley means on said blade holder and belt means on said table cooperating to effect a shifting of said blade holder at the end of each stroke of said table, and means on said blade holder and said sharpening element for controlling the rate of movement of a blade in said holder with the sharpening surface of said sharpening element at the end of each stroke, said last named means comprising rollers at each end of said holder and cams on said sharpening element which contact during one portion of movement of said table to control the movement of a blade in said holder toward or away from the sharpening surface of the sharpening element and to control the position of the sharpening element relative to the holder.

5. In a sharpening device for histological specimen blades, a moving sharpening surface, a frame for supporting the same, a blade holder, a rotatable shaft for mounting said blade holder transversely of said table, pulleys on each end of said shaft, two vertically spaced longitudinal belts on each side of said frame for contacting said pulleys, the top belt to be used on the bottom side of said pulley and the lower belt to be used on the top of said pulley alternately, and means for adjusting the tension on said belts, whereby upon movement of said sharpening surface and said frame, one set of said belts will exert pressure on said blade holder and cause rotation of the same to a different position at the end of each stroke of the sharpening surface.

6. In a sharpening device for histological specimen blades, a sharpening element having a sharpening surface, means for floatingly suspending said element, a blade holder element movable to present either side of the edge of a blade therein to said surface, means for shifting said elements relative to each other, and means on said sharpening element and means on said blade holder cooperating by mutual contact positively to position initially said sharpening element in its floating suspension during a portion of the relative movement between said elements and to gradually lower and gradually raise the blade to and from said sharpening surface.

7. In a sharpening device for histological specimen blades, a moving sharpening surface, a blade holder movable to present either side of the edge of a blade therein to said surface, means for controlling the movement of said holder toward said surface, means for adjusting said blade relative to said sharpening surface comprising a mounting for shifting said blade holder to or from said sharpening surface, a protractor positioned adjacent said mounting, and a pointer on said blade holder arranged to register on said protractor the angle of contact of said blade with the sharpening surface.

8. In a sharpening device for histological specimen blades, a sharpening element having a sharpening surface, means for floatingly sus-

pending said element, a blade holder element movable to present either side of the edge of a blade therein to said surface, means for shifting said elements relative to each other, and means on said sharpening element and means on said blade holder independent of said shifting means cooperating by mutual contact positively to po-

5 sition initially said sharpening element in its floating suspension during a portion of the relative movement between said elements prior to blade contact and to control the contact-movement between said sharpening surface and a blade in said holder element.

JULIUS LIPSHAW.
